UNITED STATES PATENT OFFICE.

GUSTAVE FABIAN ANDERSON, OF BROOKLYN, NEW YORK, ASSIGNOR TO PARAGON CAN & CAP COMPANY, INC., OF BROOKLYN, NEW YORK, A CORPORATION OF NEW YORK.

CAP-FEEDING DEVICE FOR THREADING MACHINES.

1,423,173.

Specification of Letters Patent. Patented July 18, 1922.

Application filed August 30, 1919. Serial No. 320,882.

To all whom it may concern:

Be it known that I, GUSTAVE FABIAN ANDERSON, a subject of the Crown of Sweden, and resident of the borough of Brooklyn, in the city and State of New York, have invented a new and useful Improvement in Cap-Feeding Devices for Threading Machines, of which the following is a specification.

10 This invention relates to an improvement in cap feeding devices for threading machines, with the object in view of providing such a device which includes mechanism for rapidly and accurately feeding caps to the 15 threading elements in proper position to be operated upon.

Another object consists in providing certain improvements in the form, construction and arrangement of the several parts whereby the above named and other objects may be effectively attained.

A practical embodiment of the invention is represented in the accompanying drawings, in which—

25 Fig. 1 represents a top plan view of the device.

Fig. 2 represents an end elevation of the same, partly broken away.

30 Fig. 3 represents an enlarged detail plan view, parts being shown in different positions in full and dotted lines.

Fig. 4 represents a detail elevation of the parts shown in Fig. 3 and on the same scale.

35 Fig. 5 represents a detail section of the parts adjacent the feeding end of the cap chute.

The apparatus includes a base 1 which supports a head 2 that is provided with upstanding journal supports 3, 4. The main 40 drive shaft 5 is mounted in the supports 3, 4 and secured therein by suitable bearing caps 6, 7. A stepped pulley 8 is fixed to one end of the shaft 5 for the reception of a belt 9 that is actuated from a suitable 45 source of power not shown.

A pair of brackets 10, 11 project laterally and upwardly from the head 2 and provide bearings for a shaft 12 to which is secured a gear 13. The gear 13 is in mesh with a gear 14 that is fixed on the shaft 5, so that the rotation of the latter will impart rotary motion to the shaft 12. The inner end of the shaft 12 is fashioned to constitute a threading and knurling element 15.

55 A sleeve 16 is rotatably mounted on the

shaft 5 and has a pair of extensions 17, 18 that constitute bearings for a shaft 19. This shaft has a gear 20 frictionally fixed thereto through the medium of a collar 21 and expansion coil spring 22, the latter abutting the gear 20 and washer 23 secured to the end of the shaft 19. The inner end of the shaft 19 is formed to constitute a threading and knurling element 24 that is calculated to mate with the element 15 for operating upon the caps. The gear 20 is driven from a gear 25 that is fixed on the shaft 5, through the intermediation of a gear 26 mounted on a stud that projects from a portion of the extension 18. As a result of this arrangement, 70 it will be understood that the shaft 19 is frictionally driven from the shaft 5.

The sleeve 16 is adapted to rock on the shaft 5 and it has an arm 27 projecting therefrom, which arm is bifurcated at its 75 extremity for the reception of a threaded block 28 that receives one end of a link 29. The other end of the link is threaded into a block 30 that is pivoted to one end of a bar 31. The bar 31 is fulcrumed at 32 in a lug 80 upstanding from the head 2 and its other end is pivoted at 33 to the end of a slide bar 34. A retractile coil spring 35 connects the last named end of the bar 31 with the base 1 of the machine and serves to normally swing the said end of the bar 31 inwardly and hence, through the link 29 and the arm 27, rock the sleeve 16 and extensions 17 and 18 carried thereby, to the right, 90 in Fig. 2.

The inner end of the slide bar 34 is provided with an elongated slot 36 that embraces a shaft 37 mounted in the frame 1. A cam 38 is rotatably mounted on the shaft 37 and frictionally engaged with a gear 39 95 that is keyed on said shaft. The gear 39 is actuated from the shaft 5 through gears 40, 41, the latter meshing with the gear 25 fixed on the shaft 5. The gears 40 and 41 are mounted on a stud 42 that projects from 100 the support 3.

A latch 43 has one end pivoted in the frame 1 at 44, and has its other end formed to engage a dog 45 that is carried by the cam 38. A rod 46 is secured to the latch 43 105 and has its lower end connected with a treadle arrangement (not shown) for moving the latch 43 into and out of engagement with the dog 45 on the cam 38. As a result of this last named construction, it 110

will be seen that the cam may be prevented from rotating with the gear 39 at any desired time, by the action of the operator in bringing the latch 43 into engagement with the dog 45; it being recalled that the cam 38 is only frictionally connected to the gear 39.

In the operation of the apparatus, it is intended that a cap to be threaded shall be supplied to the element 15, and then the element 24 rocked into engagement with the cap on the element 15; the contact of the said parts and rotation thereof serving to impart a thread and knurling to the cap. After the cap has been operated upon and the elements 15 and 24 separated, the cap may be ejected from the element 15 by a conventional form of ejector 47 which is actuated by a rocking bar 48 pivoted on the support 4 and having one end provided with a roller 49 that engages a cam 50 mounted on and rotated by the shaft 37.

The apparatus already described is substantially identical with that shown and described in U. S. Patent to L. R. N. Carvalho, No. 1,254,026, dated January 22, 1918, and operated in the same manner. Consequently, it constitutes no part of my present invention, but represents one form of apparatus in connection with which my invention may be used.

Referring now to the device which constitutes my invention; a cap chute 51 is adjustably supported by a bracket 52, through a pin and slot engagement 52*, the other end 35 of the bracket being fixed to the head 2.

The end of the chute adjacent the threading apparatus terminates immediately above a quadrant shaped plate 53 that is fixed on a vertical shaft 54 which is journaled in brackets 55, 56, 57, that project from the frame and head of the machine as clearly shown in Fig. 2. The shaft 54 has an arm 58 pinned thereto and projecting laterally therefrom, the extremity of the said arm being adjustably attached by a pin and slot connection 58* to one end of an extensible link 59, the other end of which is secured to a slide bar 60 that has an elongated slot 61 embracing the shaft 37. A cam 62 is fixed to the shaft 37 and adapted to engage a roller 63 that is secured to the bar 60, for actuating the said bar and link 59 secured thereto. A retractile coil spring 64 has one end fastened to the arm 58 and the other to the frame 1 and serves to normally act against the cam 62. From the immediately foregoing description, it will be seen that the shaft 54 and plate 53 are periodically oscillated, as indicated in dotted lines in Fig. 3.

The lower end of the chute 51 carries a plunger 65 (see Figs. 3 and 5) that has one end projecting into the chute and is normally urged outwardly by an extension coil spring 66. The outer end of the plunger

yieldingly bears against the face of a cam 67 that is screwed to the plate 53. The cam 67 is provided with a slot 68 in order to permit adjustment. The shape of the cam 67 is such that the plunger 65 will recede from the chute 51 as the plate 53 is moved toward the threading element 15, and the inner end of the plunger will abut the wall of the chute when the plate 53 is at the limit of its said movement. The caps to be threaded are denoted by 69, and are placed in the chute 51 in an obvious manner.

The plate 53 has a depression or recess 70 that is semi-circular in cross section and fitted to receive a cap fed from the chute 51.

In operation, the chute 51 is filled with caps either by hand or from a hopper. The caps pass down through the chute under the influence of gravity and the lowermost cap engages the plunger 65 while the plate 53 is in its outer position, shown in full lines in Fig. 3, since, in this position, the plunger is forced inwardly by the cam 67. When the machine is set in action, the plate 53 will be swung to the right in Fig. 3, and, during this motion, the plunger 65 will gradually recede from the chute 51 under the influence of the spring 66.

When the plate 53 comes near to the limit of its inward movement, shown in dotted lines in Fig. 3, the plunger 65 has moved outwardly far enough to permit a cap 69 to drop down into contact with the surface of the plate 53. As the plate 53 starts on its return movement, the plunger 65 moves inwardly and enters between the first and second caps. When the plate has reached the limit of its outward movement, the first cap will drop into the recess 70 but the plunger 65 will prevent the second and following caps from moving downwardly in the chute 51. Thus, the first cap, in dropping into the recess 70, passes completely out of contact with the succeeding cap. The plate 53 now starts on another inward movement carrying the first cap in the recess 70 and places this cap on the threading element 15 to be operated upon by the threading mechanism. As the first cap is placed on the threading element 15, the second cap is permitted to drop down into engagement with the surface of the plate 53, owing to the retraction of the plunger 65, as already described.

The continued operation of the machine causes a continued repetition of this movement, and the caps are thereby fed one at a time to the threading mechanism. This arrangement has proved to be very effective and advantageous, since it prevents a succeeding cap from contacting with the cap being fed to the threading mechanism; which contact might, and indeed frequently does, upset the first cap and thereby prevent it from being fed to the threading element in proper position.

It will be understood that various changes may be resorted to in the form, construction and arrangement of the several parts without departing from the spirit and scope of my invention and hence I do not intend to be limited to the details herein shown and described, except as they may be included in the claims.

What I claim is:

- 10 1. Apparatus of the character described comprising, a chute for the caps, threading means, a spring plunger carried by the chute for limiting the downward feed of the caps therein, an oscillating plate arranged to receive a cap from the chute and place it on the threading means, and a cam carried by said plate and fitted to engage the said plunger for permitting the caps to be fed one at a time from the chute to said plate.
- 15 2. Apparatus of the character described comprising, a chute for the caps, threading means, a spring plunger carried by the chute for limiting the downward feed of the caps therein, an oscillating plate arranged to re-
- 20

ceive a cap from the chute and place it on the threading means, and a cam carried by said plate and fitted to engage the said plunger for permitting the caps to be fed one at a time from the chute to said plate, said cam being effective to operate the plunger during the movement of said plate toward the threading means.

3. Apparatus of the character described comprising, a chute for the caps, threading means, a spring plunger carried by the chute for limiting the downward feed of the caps therein, an oscillating plate arranged to receive a cap from the chute and place it on the threading means, and an adjustable cam carried by said plate and fitted to engage the said plunger for permitting the caps to be fed one at a time from the chute to said plate.

In testimony that I claim the foregoing as my invention, I have signed my name this twenty-seventh day of June, 1919.

GUSTAVE FABIAN ANDERSON.
